TELEPHONE TRAY

Stanley Chrzanowski, New Britain, Conn.

Application June 8, 1950, Serial No. 10,416

Term of patent 14 years

(Cl. D26—14)

To all whom it may concern:

Be it known that I, Stanley Chrzanowski, a citizen of the United States of America, residing at New Britain, in the county of Hartford and State of Connecticut, have invented a new, original, and ornamental Design for a Telephone Tray, of which the following is a specification, reference being had to the accompanying drawing my new design.

Fig. 1 is a plan view of a telephone tray showing my novel new design.

Fig. 2 is an elevational edge view thereof.

Fig. 3 is a sectional end view thereof on line 3—3 of Fig. 1.

Fig. 4 is a similar view on line 4—4 of Fig. 1.

Fig. 5 is a fragmentary view showing one corner of the bottom of the tray and its associated, projecting triangular foot of which the other three corners are duplicates thereof, the bottom surface of the tray being otherwise flat.

I claim:

The ornamental design for a telephone tray, substantially as shown and described.

STANLEY CHRZANOWSKI.
